CLAIM

The ornamental design for a spoon holder, as shown and described.

DESCRIPTION

FIG. 1 is a top perspective view of a spoon holder, shown in reduced scale in environmental use, showing my new design;

FIG. 2 is a bottom perspective view thereof;

FIG. 3 is a top plan view thereof;

FIG. 4 is a bottom plan view thereof;

FIG. 5 is a front view thereof;

FIG. 6 is a rear view thereof;

FIG. 7 is a left side view thereof; and,

FIG. 8 is a right side view thereof.

The broken lines showing a spoon holder in FIG. 1 depict environmental matter that forms no part of the claimed design.
